(57) **CLAIM**

The ornamental design for a motorcycle front fork, as shown and described.

DESCRIPTION

FIG. 1 is a left frontal perspective view of a motorcycle front fork showing my new design, the right frontal perspective view being a mirror image;

FIG. 2 is a left rear perspective view thereof, the right rear perspective view being a mirror image;

FIG. 3 is a side elevational view thereof, the opposite side elevational view being a mirror image;

FIG. 4 is a front elevational view thereof; and,

FIG. 5 is a top plan view thereof.

The broken line showings of the small circles are for illustrative purposes only and form no part of the claimed invention.
